UNITED STATES PATENT OFFICE.

JAMES ANDIS GARRETT, OF TROY, TEXAS.

COTTON-SEED SEPARATOR.

SPECIFICATION forming part of Letters Patent No. 606,533, dated June 28, 1898.

Application filed November 7, 1896. Serial No. 611,357. (No model.)

To all whom it may concern:

Be it known that I, JAMES ANDIS GARRETT, a citizen of the United States, residing at Troy, in the county of Bell and State of Texas, have 5 invented a new and useful Cotton-Seed Separator, of which the following is a specification.

This invention relates to cotton-seed separators; and it has for its object to provide a new and useful machine of this character 10 having simple and efficient means for separating different sizes of cotton-seed to render the same more suitable for planting purposes.

To this end the invention, therefore, primarily contemplates a machine capable of 15 sorting or separating different sizes of seed, so that the different portions of seed delivered from the machine will be of the same size and grade, thereby obviating the slow and tedious process of separating or assorting different 20 sizes of cotton-seed by hand.

With these and other objects in view, which will readily appear as the nature of the invention is better understood, the same consists in the novel construction, combination, and 25 arrangement of parts hereinafter more fully described, illustrated, and claimed.

In the drawings, Figure 1 is a perspective view of a cotton-seed separator constructed in accordance with the present invention. 30 Fig. 2 is a central vertical longitudinal sectional view thereof. Fig. 3 is a detail in perspective of the conical conveyer-drum.

Referring to the accompanying drawings, the numeral 1 designates a separator casing 35 or box having an open bottom 2 and preferably supported on the legs 3. The said open-bottom separator-box 1 is provided in its diametrically opposite ends with the cylinder-openings 4, concentrically arranged and of 40 different sizes, so as to respectively receive therein the opposite ends of a horizontally-disposed perforate separating-cylinder 5. The separating-cylinder 5 is removably fitted at its opposite ends in the opposite openings 45 in order that it may be readily removed and replaced by the larger of said openings 4, and the said cylinder 5 is of a conical or tapering shape, the small contracted end thereof forming the discharge or delivery end, through 50 which the larger sizes of seed are delivered during the operation of the machine. The perforate conical stationary separating-cylinder-

5 is covered at its large open end by a cap-piece 6, detachably fastened to one end of the casing 1 by means of screws 7 or other suitable fasteners, and said cap-piece 6 has formed therein a bearing-opening 8, disposed in horizontal alinement with a bearing-opening 9, formed in a bearing-bar 10, secured to one end of the casing 1 and extending across the small 60 open end of the cylinder 5.

The alined bearing-openings 8 and 9 are adapted to receive therein the spindle extremities of a rotary conical conveyer-drum 11, arranged to rotate within the cylinder 5 65 and of a size nearly equaling that of the cylinder. The conical conveyer-drum is provided with a peripheral series of regularly-spaced agitator fingers or spikes 12, arranged on a spiral line from end to end of the drum 70 and adapted to work in close proximity to the inner periphery of the cylinder 5, so as to agitate the seed and cause the smaller sizes thereof to be forced through the openings or slots in the cylinder, while at the same time 75 serving to positively force the larger sizes of seed toward and out through the small end of the cylinder.

It is to be observed that the perforate separating-cylinder 5 lies within the casing 1 out 80 of contact with the top and sides thereof, so that separations of the seed can occur at any point throughout the periphery of the cylinder and fall through the open bottom of the casing, and it is important in this connection 85 that the drum 11 is provided with a solid body to form a narrow space between the surface thereof and the inner surface of the perforate cylinder, in which the cotton-seed is confined and worked against the cylinder by 90 the agitator fingers or spikes 12.

The rotary conveyer-drum has fitted to the large end thereof an operating-crank 13, having a handle 14 and pivotally connected with the lower end of a link 15, the upper end of 95 which link connects with a crank-arm 16 at the outer end of a stirrer-shaft 17, mounted transversely within a feed-hopper 18. The feed-hopper 18 is mounted on top of the casing 1, over the top feed-opening 19, communicating with the interior of the drum 5 at the large or flared end thereof, and fitted within the bottom of the hopper 18, over the feed-opening 19, is a slotted plate 20, in which

works a plurality of stirrer-fingers 21, carried by the shaft 17 and serving to stir up the seed within the hopper to prevent clogging and to force the same through the feed-opening 19 into the cylinder 5, as will be readily understood.

The cylinder 5 is designed to be interchangeable with duplicate cylinders having openings or slots of different sizes, whereby 10 the machine can be used in connection with different grades of cotton-seed, it being obvious that by removing the cap-piece 6 and the cylinder 5 within the casing a cylinder with the proper-sized openings or slots may 15 be readily inserted in place. In the operation of the machine the large sizes of seeds, which will not pass through the opening or slots of the screen-cylinder, are conveyed toward the contracted end of such cylinder and 20 discharged therethrough, while the smaller sizes of seed and other separations are worked through the cylinder and fall through the open bottom 2 of the cylinder.

In order to insure the proper separation of 25 the different sizes of seed, it is necessary that the cylinder 5 be perforated with slots that are disposed annularly thereof in circular rows instead of lying longitudinally or lengthwise of the cylinder, which latter disposition 30 of the slots 2 would not permit of the smaller sizes of the seed being worked through the cylinder as the seed is conveyed through the narrow space between the periphery of the drum and the cylinder. It will be further 35 observed that the transverse or annularly-disposed slots of the separating-cylinder 5 present an abrading and sifting surface which insures a scouring or cleaning action as well as a separating action for the seed, it 40 being understood that the thorough scouring or cleaning of the seed is very desirable to provide for placing the seed in the best possible condition for planting. In connection with the proper disposition of the slots or 45 perforations in the cylinder it is important to note that said cylinder, which is arranged in a horizontal position, confines between itself and the conical drum a comparatively narrow uniform working space from feed to 50 discharge, whereby the area of said working space is gradually contracted from feed to

discharge and the mutual pressure and attrition of the material under treatment is maintained.

Changes in the form, proportion, and the 55 minor details of construction may be resorted to without departing from the principle or sacrificing any of the advantages of this invention.

Having thus described the invention, what 60 is claimed, and desired to be secured by Letters Patent, is—

1. In a cotton-seed separator, the combination of the horizontal conical drum armed with spiral rows of fingers or spikes, the horizontal conical cylinder formed with transverse perforations presenting an abrading and sifting surface, and a uniform working space between itself and the cylinder from feed to discharge, whereby the area of said working 65 space is gradually contracted from feed to discharge and the mutual pressure and attrition of the material under treatment is maintained, and a feeder placed at the larger end of the separating-cylinder, substantially as 70 set forth.

2. In a cotton-seed separator, the combination of an open bottom casing, a stationary horizontal conical separating-cylinder arranged within the casing out of contact with 80 the top and sides thereof and formed with transverse perforations presenting an abrading and sifting surface, a horizontal conical drum arranged within the cylinder and armed with spiral rows of fingers or spikes, said 85 drum forming between its periphery and the perforate cylinder a uniform working space extending from feed to discharge whereby the area of said working space is gradually contracted from feed to discharge and the 90 mutual pressure and attrition of the material under treatment is maintained, and a feeder placed at the larger end of the cylinder, substantially as set forth.

In testimony that I claim the foregoing as 95 my own I have hereto affixed my signature in the presence of two witnesses.

JAMES ANDIS GARRETT.
